UNITED STATES PATENT OFFICE

2,620,988

FLUORESCENT LAMP BULB
BREAKING DEVICE

Edgar H. Tellier, Milwaukee, Wis.

Application January 10, 1950, Serial No. 137,776

1 Claim. (Cl. 241—62)

1

This invention relates to breaking devices and particularly to a device for breaking glass fluorescent tubes.

The disposal of fluorescent bulbs presents a very dangerous procedure particularly when the bulbs are broken and a person comes in contact with the gas escaping from the bulbs. Breathing of this gas presents occupational hazards that may cause severe physical discomfort and possible serious consequences to a person's health and well being. Therefore an object of this invention is to provide a device whereby the fluorescent tube may be broken into small particles and the gas be absorbed or confined within a medium where a person will not come into contact with the escaping gas.

A further object of this invention is to provide an enclosure into which a fluorescent tube may be inserted in conjunction with a constant stream of water whereby as the tube is inserted further into the enclosure it is gradually broken up by a rotating breaking means and the broken glass together with the gas in the tube is washed down into a container or receptacle having an open drain through which the water and absorbed gas is permitted to flow into a drain leading to a sewer.

A still further object of the invention is to provide a fluorescent glass tube breaking device comprising a frame for detachably mounting a water pan provided with open drain holes and having a top support for mounting a motor and a hollow enclosure. The enclosure rotatably supports a breaking member secured to a shaft which is rotated by means of a motor through a pulley and drive belt arrangement. The enclosure is provided with an enlarged aperture at the top for threadedly mounting an elongated tubular member open at both ends and of sufficient diameter to permit easy insertion of the conventional type of fluorescent tubes. The tubular member is also provided with an aperture through its side for mounting a connection for communication with a water source. The entire device provides means for the gradual breaking of the fluorescent tubes, and the absorbing, through the water, of the gas in the tube and facilitating the easy disposal of the gas and water through the drain into the receptacle containing the broken glass.

Another object of this invention is to provide a fluorescent tube breaking device that is rugged but economical to construct, easy to operate and satisfactory for the purposes intended.

Other and further objects of this invention will become apparent from the following detailed

2

description of one illustrative embodiment of the invention when considered with the accompanying drawings wherein:

Figure 1 is a view in perspective of the assembled unit constituting the invention.

Figure 2 is a cross-sectional view of the invention, and

Figure 3 is a side elevational view in cross-section of the assembled unit constituting the invention.

The assembled breaking device of one form of applicant's invention is designated by the numeral 10 and comprises a rectangularly supporting frame 11 including vertical members 12 and base members 13 and a top support plate 14. The support plate 14 is apertured at 15 for receiving an open end of an annular shaped enclosure member 16. The member 16 is perforated again at 17 along its outer periphery for threadedly mounting a tubular member 18. The member 18 is open at both ends and is provided with an opening at 19 along the surface thereof. The opening 19 is connected to a water source through a hose 20. The annular enclosure 16 has a pair of bearings 21, one each of which is centrally disposed within the side walls 22 and provide support for a horizontal shaft 23 passing through the members for rotatably mounting a star-shaped breaking wheel 24. The wheel 24 may be keyed or otherwise secured to the shaft 23 in any suitable manner. In operation, this wheel rotates freely within the member 16. Flange means 25, integral with member 16, bear upon the top support plate 14 when the member 16 is in operative position.

The shaft 23 extends through and beyond one side of the member 16 and supports a pulley 26 having a V-shaped outer peripheral surface for engaging a belt 27 which also engages the outer surface of a second pulley keyed to the drive shaft 29 of a prime mover shown as a motor 30. A safety belt guard 31 is mounted over the pulleys and belt and is secured to the top support plate 14 by suitable fastening elements shown as 32.

A slidably supported pan 33 open at the top may be readily mounted within the frames 11 and is in direct communication with the opening 15 in the member 16. Drain apertures 34 are arranged in the front wall 35 of the pan 33 adjacent its bottom surface whereby water may readily flow or drain from the pan 33. Also arranged on the front wall 35 is a handle 36 with which the pan may be readily removed from the frame.

In operation, the prime mover 30, which is connected to any suitable electrical outlet, is actuated causing the pulley thereon to rotate and accordingly the belt 27 rotates the pulley 26, causing the wheel 24 to rotate within the member 16. Any suitable water valve disposed within the hose 20 is then opened permitting water to flow through the hose 20 into the tubular member 18. This water flows down into the annular member 16, is whirled around by the wheel 24 and discharged through the opening 15 into the water receptacle 33. From the receptacle the water is discharged through the drain holes 34 to any suitable source of disposal. A fluorescent tube shown as 35 may be inserted into the tubular member 18 from its top opening and pushed down against the wheel 24. As the wheel 24 breaks the tube 35, the gas contained in the fluorescent tube escapes and is immediately absorbed by the water which carries the absorbed gas along the path, heretofore described, for easy disposal. The broken glass from the fluorescent tube is washed down into the receptacle 33. When it is desired to dispose of the glass, the receptacle 33 is simply pulled out from the frame 11 and the contents emptied in any convenient place.

It will be seen, therefore, that the applicant has provided an apparatus that readily adapts itself to the breaking of useless fluorescent tubes, and has means for absorbing and disposing of the dangerous gas confined within the fluorescent tube.

Obviously, many changes may be made in the form, construction and arrangement of the parts constituting the device without departing from the spirit of the invention or sacrificing any of its advantages, and the right is hereby reserved to make such changes, as fairly fall within the scope of the appended claim.

Having thus described my invention, what I claim and desire to secure by Letters Patent of the United States is:

A device for breaking fluorescent tubes provided with means for absorbing and disposing of the gas contained in said tube, said device

comprising, a frame, a removable water pan, said water pan slidably mounted within said frame, said pan having a plurality of drain holes adjacent its bottom surface, said frame provided with a top support plate, said support plate having an aperture, a material breaking member mounted within a housing, said breaking member including a rotatable star shaped wheel, said housing having a bottom opening and a side opening, said housing mounted on said support and having said bottom opening communicating with the aperture in said plate, a tubular member, said tubular member open at both ends with one end secured to the side opening in said housing, said tubular member provided with an opening in its side, a hose connected with a water source, said hose communicating with side opening in said tubular member, said water flowing freely through said tubular member, into said housing and through said drain holes, a motor, said motor secured to said top support plate and arranged to actuate said breaker wheel.
